UNITED STATES PATENT OFFICE

140,653

DESIGN FOR A CARRIER FOR HEARING-AID OR BATTERY

Miriam Corre, Chicago, Ill.

Application May 22, 1944, Serial No. 113,704

Term of patent 14 years

(Cl. D26—14)

To all whom it may concern:

Be it known that I, Miriam Corre, a citizen of the United States of America and a resident of the city of Chicago, in the county of Cook and State of Illinois, have invented a new, original, and ornamental Design for a Carrier for Hearing-Aid or Battery, of which the following is a specification, reference being had to the accompanying drawing, forming part thereof.

In the drawing:

Fig. 1 is a front elevational view of a carrier for

a hearing-aid or for the battery, showing my new design.

Fig. 2 is a rear elevational view of said carrier, showing this design.

Fig. 3 is a side elevational view thereof.

The dominant features of my design reside in the portions shown in full lines.

I claim:

The ornamental design for a carrier for hearing-aid or battery, as shown and described.

MIRIAM CORRE.
